UNITED STATES PATENT OFFICE.

JULIUS DORNETH, OF BERLIN, GERMANY, ASSIGNOR TO TYPOGRAPH GESELLSCHAFT
M. B. H., OF BERLIN, GERMANY, A CORPORATION OF GERMANY.

MATRIX-LINE SETTING AND CASTING MACHINE.

1,108,556.

Specification of Letters Patent. Patented Aug. 25, 1914.

Application filed December 29, 1913. Serial No. 809,391.

To all whom it may concern:

Be it known that I, JULIUS DORNETH, a subject of the German Emperor, and residing at Berlin, Germany, have invented certain new and useful Improvements in Matrix-Line Setting and Casting Machines, of which the following is a specification.

In matrix-line setting and casting machines having matrices guided on wires, the line, after it is cast, is freed from the bur adhering to it at the upper portion carrying the characters, by passing between two adjustable knives. The holder carrying the knives, is secured to a slide block which is arranged near the casting point coinciding with the setting point. At this point however there are arranged in a very limited space, various other parts, so that this part of the machine is not easily accessible for the various manipulations which have to be effected. When the line is cast, the casting mold holder with the finished line and the casting pot are moved to their original position. Before however the casting mold holder reaches its initial position, the slide block carrying the knife holder passes over the partly ejected line still contained in the casting mold, in order to remove the bur adhering to it. The opening of the casting pot filled with liquid, lead, is, in the advanced position of the slide block, exactly above it, so that the compositor, when loosening the screw by means of which the knife holder is secured to the slide block, is liable to injure himself by contact with the hot casting pot. Another disadvantage is that this method of securing is very tedious and lengthy.

The invention is intended to obviate these disadvantages, and to enable the knife holder to be quickly replaced. To the end, the knife holder is not firmly screwed to the slide block as hitherto, but is loosely mounted in a slot or a guide of the slide block and held therein by an easily folding bracket which is pivotally mounted on the slide block.

A construction according to this invention is illustrated in the accompanying drawing in which,

Figures 1 and 2 show it respectively in side elevation and plan, Fig. 3 in end elevation seen from the left, with the bracket omitted, and Fig. 4 shows the arrangement on the machine.

The knife holder *a* is mounted on a slide block *g*, which is reciprocated in the known manner over the type line *d* by an oscillating lever *h* from the main spindle of the machine. It is provided with adjustable knives *c*, *c'* secured by screws *b*, *b'* and passing over the upper portion of the type line *d*. Above the knife holder *a*, a set screw *e* is mounted which is introduced into the slot *f* open in front of the slide block *g* (Fig. 2). In the end or working position of the knife holder *a*, a bracket *h* pivotally mounted on the slide block *g*, is placed around the said screw *e*, whereby the knife holder *a* is held fast in that position. The bracket *h* is held in the closing position by a spring controlled pin *i* (Fig. 2). The compositor therefore merely has to raise the bracket (Fig. 1) with one hand and then the knife holder *a* can be removed easily with the other hand from the slide block *g*.

75

I claim herein as my invention:

1. In apparatus for trimming type lines in matrix line setting and casting machines, the combination of two knives located one on each side of the type line to be trimmed, so a holder for said knives, means to reciprocate said holder, and a detachable device to connect the holder to the reciprocating means.

2. In apparatus for trimming type lines in matrix line setting and casting machines, the combination of two knives located one on each side of the type line to be trimmed, a holder for said knives, a member to carry said holder, means to reciprocate said member, and a device pivoted to said member and adapted to detachably connect the holder to the member.

3. In apparatus for trimming type lines in matrix line setting and casting machines, the combination of two knives located one on each side of the type line to be trimmed, a holder for said knives, a rod to carry said

holder, a hook pivoted to said rod, a projection on the holder adapted to detachably engage the hook, means to reciprocate said rod, and a locking pin in the hook for the purpose set forth.

In witness whereof, I have hereunto signed

my name in the presence of two subscribing witnesses.

JULIUS DORNETH.
